ALKYLATION PROCESS EMPLOYING
EVAPORATIVE COOLING

David H. Putney, Kansas City, Mo., assignor to
Stratford Development Corporation, Kansas
City, Mo., a corporation of Delaware

Application March 14, 1942, Serial No. 434,655

3 Claims. (CL 260—683.4)

This invention relates to improvements in an alkylation process employing evaporative cooling and refers more particularly to a method for applying direct evaporative refrigeration to the acid and hydrocarbon effluent discharged from an alkylation reaction, for the purpose of building up the iso-butane-olefin ratio in the reaction zone and eliminating all heat transfer surfaces from the reaction zone.

It has been found that, by passing the hydrocarbon and acid effluent from an alkylation reaction zone into a flash zone operated at reduced pressure, a portion of the volatile hydrocarbon components can be evaporated and the heat of vaporization being supplied by a drop in temperature of the acid and remaining hydrocarbon to such an extent that the reduced temperature of the acid which is then returned to the reaction zone, will carry the entire refrigeration load required to operate the alkylation reaction at optimum temperatures. The vapors separated during the evaporation are rich in iso-butane, due to the high iso-butane content of the hydrocarbon effluent. The condensate recovered from these vapors can be recycled as a part of the charge to the alkylation reaction stage for building up the concentration of iso-butane in the feed in the same manner as the iso-butane recycle recovered from fractionation of the alkylate is used to accomplish the same result. This is particularly true when alkylating feed stocks which result in a low concentration of normal butane in the effluent.

Other so-called autorefrigerated or evaporative cooling systems have been developed for alkylation processes and some are at the present time being utilized in commercial plants. In these, however, the volatile hydrocarbon components are directly evaporated from the alkylation zone. The refrigerant therefore does not exist as a liquid in the effluent discharged from the reaction zone but is removed as a vapor from the reaction as fast as it is introduced. Condensed refrigerant recovered from the evaporated materials therefore does not increase the iso-butane-olefin ratio in the reaction zone.

As distinguished from this type of evaporative cooling, the present method proposes to take full advantage of the iso-butane refrigerant during its passage through the reaction and catalyst-settling stages as it exerts in both stages an influencing factor favorable to the production of iso-octane in the reaction zone and as a fluid medium advantageous to more complete settling in the acid settler.

Another advantage of the present method is the elimination of all heat transfer surfaces from the reaction circuit, thus making for simplicity and reduction of equipment cost particularly in cases of large installations where multiple reactors and multiple tube bundles would otherwise have to be employed.

Further advantages of the process will appear from the specification.

The single figure, which forms part of the specification and is to be read in conjunction therewith, is a schematic flow diagram of an apparatus adapted to the operation of the process.

For purposes of illustration but not by way of limitation and for convenience in phraseology, we will refer to the iso-paraffinic hydrocarbon as iso-butane and we will refer to the olefinic hydrocarbon as butylene, it being understood that any of the iso-paraffinic hydrocarbons may be alkylated by means of any of the olefinic hydrocarbons.

Referring to the drawing and describing the process in connection therewith, a normally gaseous feed stock having a substantial content of olefinic hydrocarbons is charged from any convenient source through the pipe 1 and is mixed in pipe 2 with a second normally gaseous feed stock containing iso-paraffinic C₄ hydrocarbons supplied through pipe 3. This mixture in liquid phase is accumulated in a feed tank 4 from which it is withdrawn through pipe 5 and charged by means of pump 6 through line 7 in which is interposed a heat exchanger 8 and a flow control valve 9. A fluid medium, such as the cold hydrocarbon effluent leaving the system, is circulated in heat exchange relation with the feed in the exchanger 8 to bring it to a proper temperature for alkylation in the contactor 10.

A condensation catalyst, such as sulfuric acid, hydrofluoric acid, phosphoric acid, aluminum chloride, or other catalysts which promote the alkylation reaction, is introduced through pipe 11. In the description of the process and apparatus, for convenience and in the interest of simplifying the specification, the catalyst will be specified as sulfuric acid, but it is contemplated that hydrofluoric acid or any of the other catalysts suggested may be used.

In the contactor is a cylindrical baffle 10a shown in dotted lines, in the lower, open ended, constricted throat of which is positioned a propeller 12, mounted on shaft 13 and driven through a gear drive, diagrammatically shown at 14 by means of a motor 15. By this mechanism

an intimate mixture of the paraffinic and olefinic hydrocarbons with the condensation catalyst is effected in the contactor by rapid circulation of the constituents upwardly through the passageway formed by the cylindrical baffle 10a within the contactor 10.

The character of the feed stock, the catalyst used, the iso-butane-olefin ratio, and the acid concentration form no part of the present invention except that these factors should be regulated to obtain optimum conditions for alkylation in the contacting stage.

To maintain the temperature of reaction within a proper range is the function of the evaporative cooling contemplated by the instant method. The mixture of reacted hydrocarbons and catalyst forming the effluent from the reaction zone or contactor 10 is discharged through pipe 16 and the catalyst separated from the lighter hydrocarbon constituents in the acid settler 17. To the acid settler, fresh catalyst is supplied through pipe 18 controlled by a valve 19. Acid settled from the mixture is withdrawn through pipe 20. Spent acid in an amount equal to the fresh acid feed may be continuously or periodically discharged through pipe 21 controlled by a valve 22. That normal acid recycle demanded for good operation is charged by means of pump 23, lines 24 and 25, to a flash tower 26. Between pipes 20 and 24 is a pipe 27 controlled by a valve 28 which bypasses the pump 23. Valve 29 in line 24 and valve 30 in line 20 control the flow of acid through their respective lines. Since the flash tower is normally operated at a pressure lower than the pressure on the acid settler 17, the pump 23 will be bypassed through line 27. A flow control valve 31 in line 24 serves to regulate the amount of catalyst supplied to the flash tower. The lighter hydrocarbon materials separated in the acid settler from the catalyst are withdrawn through pipe 32, regulated by valve 33 and introduced into a tray in the upper part of the tower. Reduced pressure is maintained in the tower by means of a compressor 34 taking suction through the overhead line 35 and discharging volatile hydrocarbon components into a condenser 36 through pipe 37. The liquid condensate from the condenser is discharged through line 38 to the feed tank 4.

The catalyst supplied to the flash tower 26 cascades down over a series of trays and is accumulated in the bottom of the tower where there is maintained a lower acid level by the liquid level control device 39, and an upper liquid level of hydrocarbon materials by means of liquid level control device 40. The heavier acid is withdrawn from the bottom of the tower through pipe 41 and is recycled by pump 42 through pipe 41, the valve which controls liquid level 39 being interposed in this latter line. The unevaporated alkylate containing hydrocarbon mixture is withdrawn from the tower 26 through pipe 43 and is discharged by pump 44 through line 45 to the final settler 46. In the pipe 45 is interposed a control valve which is regulated by the liquid control device 40. Any entrained liquid catalyst, separated in the final settler 46, is returned through pipe 47 to pipe 41 for recycling to the alkylation stage.

As explained, in the flash tower 26 there is maintained a lower acid level and an upper hydrocarbon level. Since the base of the flash tower is not an ideal settler, it is proposed to take the hydrocarbon alkylate from the flash tower through the final settler 46 for the purpose of al-

lowing any acid carryover to settle from the hydrocarbons before the hydrocarbon is passed to the neutralization and fractionation equipment. The small amount of acid settled out in the final settler 46 can be either continuously or periodically passed to the acid pump 42 and returned to the contactor. It does not matter if some hydrocarbon is entrained in the acid being returned to the contactor from the base of the flash tower or from final settler 46.

The alkylate containing hydrocarbon mixture separated in the final settler 46 is passed through line 48, through a heat exchanger 49 which may be identical to exchanger 8 as previously suggested, and pipe 50 to neutralization and fractionation equipment diagrammatically shown by the rectangular block 51.

This equipment normally will include the conventional soda mixing, settling equipment and fractionation equipment, such as a depropanizer, a de-isobutanizer, stabilizer, and rerun towers. Iso-butane recovered from fractionating equipment, is recycled through pipe 52 to the feed tank 4. Normal butane is diverted from the system through pipe 53 controlled by valve 54. C₃ fractions and lighter are diverted through pipe 55 controlled by valve 56. Materials within the alkylate range are recovered through pipe 57, regulated by valve 58, and the bottoms from the alkylate rerun tower are taken off through pipe 59, controlled by valve 60.

It is inadvisable to pass the mixture of hydrocarbon and acid effluent from the contactor 10 direct to the flash tower 26 for the reason that the mixture leaving the contactor is in the form of a hydrocarbon in acid emulsion. A reduction of pressure on such an emulsion would cause boiling and foaming of the acid and possibly result in acid foam carrying over to the compressor 34. This emulsion is therefore passed first to an acid settler 17 where it is settled into a clear hydrocarbon and a "flat" acid. These two streams are passed to the flash tower through pipes 32 and 24 where they come in contact with each other but are not mixed to the extent that an emulsion is formed. The flash tower can thus be operated without foaming and the hydrocarbon and acid can be readily separated after being chilled.

The necessity of making a separation of the acid and hydrocarbons as in the settler 17 between the reactor 10 and flash tower 26 depends largely upon the degree of mixing or emulsification in the reactor. In some cases the mixture leaving the reactor may be of such nature as to permit its introduction directly to the flash tower 26 without separation. If the settler 17 is eliminated the fresh acid feed could be supplied either to the flash tower 26 or contactor 10 and the spent acid removed from line 41.

The contactor, acid settler and final settler are operated liquid-full, under pressure. The flash tower is operated at reduced pressure and in the case of C₄ alkylation, at from 8 to 15 pounds absolute.

As an example, when this method is used to alkylate a C₄ feed stock having between 16 and 20% normal butane in the effluent from the contactor 10, the following conditions may exist: Reaction temperature of 50° F.; per cent acid in the mix, 60%; temperature of the acid returned to the contactor, 13° F. to 15° F.; pressure on the flash tower, 10 to 12 pounds per square inch absolute; external ratio iso-butane to olefin built up by fractionation, ranging between 3.0/1 to 3.5/1; external ratio of feed stock

including compressor condensate 11/1; iso-butane content of effluent 65% to 75%.

An inspection of the above conditions shows them to be proper for the production of the exceptionally high quality alkylate and depending upon the nature of the C₄ olefins the alkylate would be expected to contain a raw aviation fraction of between 94 to 96 octane by A. S. T. M.-C. F. R. method. Such high quality alkylate could not normally be made from a feed stock having an external ratio of only 3.0/1 to 3.5/1. It is only by virtue of the compressor condensate being returned to the feed that the ratio is raised to approximately 11/1 and the quality thus improved. Furthermore, the existence of the paraffinic hydrocarbons in liquid form, both in the reaction and settling stages as contrasted with evaporative cooling methods which exhaust these materials from the reaction stage has a very decided advantageous effect upon the character of the final alkylate produced.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, I claim:

1. A method of alkylating iso-paraffinic hydrocarbons with olefinic hydrocarbons comprising the steps of intimately contacting the iso-paraffinic and olefinic hydrocarbons in a reaction step in the presence of a condensation catalyst at a predetermined temperature, withdrawing the reacted products and catalyst from the reaction step and passing them to an intermediate separating step under pressure sufficient to maintain them in liquid phase and there separating the catalyst from the hydrocarbons, separately introducing said catalyst and hydrocarbons into a reduced pressure zone at points spaced far enough apart to prevent the formation of an emulsion and foaming, vaporizing a portion of said hydrocarbons by the reduction in pressure and thereby cooling the catalyst, returning the cooled catalyst to the reaction step, and controlling the temperature and quantity of said recycled cata-

lyst as a function of the required temperature in the reaction step.

2. A method of alkylating iso-paraffinic hydrocarbons with olefinic hydrocarbons comprising the steps of intimately contacting the iso-paraffinic and olefinic hydrocarbons in a reaction step in the presence of a condensation catalyst at a predetermined temperature, withdrawing the reacted products and catalyst from the reaction step and passing them to an intermediate separating step under pressure sufficient to maintain them in liquid phase, and there separating the catalyst from the hydrocarbons, separately introducing said catalyst and hydrocarbons into a reduced pressure zone at points spaced far enough apart to prevent the formation of an emulsion and foaming, vaporizing a portion of said hydrocarbons by the reduction in pressure and thereby cooling the catalyst, recycling the vaporized hydrocarbons to the reaction step as a constituent of the feed thereto, returning separately the cooled catalyst to the reaction step, and controlling the temperature and quantity of said recycled catalyst as a function of the required temperature in the reaction step.

3. A method of alkylating iso-paraffinic hydrocarbons with olefinic hydrocarbons comprising the steps of intimately contacting the iso-paraffinic and olefinic hydrocarbons in a reaction step in the presence of a condensation catalyst at a predetermined temperature, withdrawing the reacted products and catalyst from the reaction step and passing them to an intermediate separating step under pressure sufficient to maintain them in liquid phase, and there separating the catalyst from the hydrocarbons, separately introducing said catalyst and hydrocarbons into a reduced pressure zone at points spaced far enough apart to prevent the formation of an emulsion and foaming, vaporizing a portion of said hydrocarbons by the reduction in pressure and thereby cooling the catalyst, recycling the vaporized hydrocarbons to the reaction step as a constituent of the feed thereto, returning separately the cooled catalyst to the reaction step, controlling the temperature and quantity of said recycled catalyst as a function of the required temperature in the reaction step, supplying fresh catalyst to the system, and removing spent catalyst in corresponding amounts to maintain a relatively constant concentration of catalyst in the reaction step.

DAVID H. PUTNEY.
